UNITED STATES PATENT OFFICE.

CARL L. RASMUSSEN, OF BUTTE, MONTANA.

ALARM-CLOCK ATTACHMENT.

1,397,702.

Specification of Letters Patent.

Patented Nov. 22, 1921.

Application filed July 30, 1920. Serial No. 400,019.

To all whom it may concern:

Be it known that I, CARL L. RASMUSSEN, a citizen of the United States of America, residing at Butte, in the county of Silver Bow and State of Montana, have invented new and useful Improvements in Alarm-Clock Attachments, of which the following is a specification.

This invention comprehends the provision of an alarm clock attachment in the nature of an electric lamp and switch therefor, which is automatically actuated with the sounding of the alarm to illuminate the lamp.

Another important object of the invention resides in the provision of an attachment of the above mentioned character which can be quickly and easily associated with the clock without in any way reconstructing the latter, and removed from the clock as the occasion may require.

The nature and advantages of the invention will be better understood when the following detailed description is read in connection with the accompanying drawing, the invention residing in the construction, combination and arrangement of parts as claimed.

In the drawings forming part of this application, like numerals of reference indicate similar parts in the several views, and wherein:

Figure 1 is a rear elevation of a clock showing the attachment applied thereto with the parts in normal position.

Fig. 2 is a side elevation.

Fig. 3 is a top plan view.

Fig. 4 is a vertical sectional view taken on line 4-4 of Fig. 1.

Fig. 5 is a transverse sectional view taken on line 5-5 of Fig. 1.

Fig. 6 is an enlarged fragmentary view showing the position of parts when the switch is closed.

Referring to the drawings in detail, A indicates an alarm clock of the usual well known construction and wherein 10 indicates the alarm winding key, in conjunction with which the attachment forming the sub-

ject matter of the invention is used. The attachment embodies a base 11 of suitable insulating material, which is secured to the top of the clock A in any suitable manner, preferably by means of a pair of clips 12 secured to the underside of the base 10 and

engaging the edge of the body of the clock

as shown. Mounted upon the base 11 is the socket 14 for the electric light bulb 15, the socket being of the well-known construction except that it is provided with a fixed contact which projects beyond the socket and against one of the edges of the base 11. Pivotaly mounted upon the same edge of the base is a movable contact 16 which when moved into engagement with the fixed contact 17 closes the circuit to illuminate the lamp as will be readily understood. The conducting wires 18 are terminally connected to the movable switch into the socket, these wires having a plug 18' which may be connected up with any suitable source of energy.

Loosely mounted upon the stem of the alarm winding key 10, is an eccentric 19 having a peripheral groove 20 which receives the looped extremity 21 of an operating element 22 which controls the movement of the movable contact 16. For this purpose, the operating element 22 operates through an opening 23 in the base 11, and has its adjacent extremity offset as at 24 to overlie the movable contact 16. Projecting from the eccentric 19 is a pin 25 which is disposed in the path of movement of the key 10. In practice, the movable contact 16 is arranged above the fixed contact 17, being held in this position frictionally and in which position of parts the offset extremity of the operating element rests against the adjacent edge of the movable contact. At the moment when the alarm sounds, the key 10 rotates toward the right, and by reason of the fact that the pin 25 is disposed in the path of movement of this key, the eccentric 19 is turned upon the stem moving down on the operating element 22 with the result that the movable contact 16 is brought into engagement with the fixed contact 17. The circuit is thus closed and the lamp 15 illuminated as will be readily understood. The construction is such that the alarm can be rewound without interference on the part of the attachment, and the movable contact 16 can be moved below the base when in active position and out of the way while the alarm is being rewound. The invention is in the form of an attachment which can be manufactured and sold at a nominal cost and applied to any make of alarm clock without injuring the construction of the latter.

While it is believed that from the fore-

going description the nature and advantages of the invention will be readily understood, I desire to have it known that I do not limit myself to what is herein shown and described, and that such changes may be resorted to when desired as fall within the scope of what is claimed.

What I claim is:

1. An alarm clock attachment comprising a base, means carried by the base for securing it to the clock, a lamp socket supported by the base, a switch including a fixed contact carried by the base, a movable contact pivoted on said base, an operating element 10 associated with and actuated by the alarm winding stem incident to rotation thereof in one direction, and an offset extremity carried by said operating element and overlying one edge of the movable contact for the purpose 15 specified.
2. An alarm clock attachment comprising a lamp socket mounted on the clock, a switch including a fixed contact, a movable contact mounted for pivotal movement, an eccentric 20 loosely mounted upon the alarm winding 25

stem, a pin projecting from said eccentric and arranged to be engaged by the key and said stem when rotated in one direction to rotate said eccentric, an operating element for said movable contact, said element being connected with and operated by said eccentric, and said element having an offset extremity overlying one edge of the movable contact for the purpose specified.

3. An alarm clock attachment comprising a base member secured to the clock, a lamp socket carried by the base, a switch including a fixed contact associated with the base, and a movable contact pivoted thereon, an eccentric loosely mounted upon the alarm 30 winding stem, said eccentric having a circumferential groove, an operating element for said movable contact, said element terminating to provide a loop received by said groove, and the opposite end of said element being offset to overlie one edge of the movable contact for the purpose specified.

In testimony whereof I affix my signature.

CARL L. RASMUSSEN.
